ARCHITECTURAL DECORATIVE PANEL OR THE LIKE

Joseph M. Krippendorf, Penn Hills, Pa., assignor to Aluminum Company of America, Pittsburgh, Pa., a corporation of Pennsylvania

Filed Oct. 22, 1963, Ser. No. 77,089

Term of patent 14 years

(Cl. D13—1)

FIG. 1

FIG. 2

FIG. 4

FIG. 1 is a front elevational view of an architectural decorative panel or the like showing my new design;

FIG. 2 is an end elevational view of the panel of FIG. 1;

FIG. 3 is a side elevational view of the panel of FIG. 1; and

FIG. 4 is a perspective view of the decorative panel of FIGS. 1, 2 and 3.

I claim:

The ornamental design for an architectural decorative panel or the like, substantially as shown.
